JEWETT G. P. EVANS, OF FORT WORTH, TEXAS.

METHOD AND MEANS FOR MAKING PHOTOGRAPHIC NEGATIVES.

Application filed May 23, 1925. Serial No. 32,867.

To all whom it may concern:

Be it known that I, JEWETT G. P. EVANS, citizen of the United States of America, residing at Fort Worth, in the county of Tarrant and State of Texas, have invented certain new and useful Improvements in Methods and Means for Making Photographic Negatives, of which the following is a specification.

10 This invention relates to new and useful improvements in method and means for making photographic negatives.

In the making of photographic plates for the production of half tone cuts the sensitized plate is exposed through a screen so that the plate when developed will depict the subject photographed by means of small squares called "dots." It has been found that some parts of a subject photograph faster than others and there is danger of over exposure as well as under exposure; therefore it has been the best practice to make a plurality of exposures through stops of different diameters so that high lights or tones, low lights or tones and intermediate tones may be reproduced with equal value. However such a method required great skill in arriving at the best size of stop and the most desirable length of exposure and further the results are quite uncertain and invariably the objects appearing on the plate have more or less flatness and particularly where a coarse screen, say of 60 mesh, is used.

15 It is of course understood that light rays as reflected through a lens range from the highest white light, so called, to the lowest or darkest light or shadow. The range of tones intermediate and including these extremes are known as gradations. These gradations each have a proportionate value one to the other and it will be readily seen that the recording on a sensitized plate of one with a greater or less density than another, would produce over or under exposure, flatness and lack of detail or technique.

20 In explaining my invention it is pointed out that it has particularly to do with the making of half tone negatives for photo engraving purposes in which the sensitized plate is exposed through a line screen. The relation of this screen to the sensitized plate has a controlling influence on the size of

aperture used and it becomes necessary to adjust the bellows and vary the size of the opening of the diaphragm for different subjects.

25 It has been found by actual experience that the high or whitest lights which cause the largest dot on the negative, will photograph to perfection in size and opacity and while the lesser or darker tones causing the smaller dots will photograph to the correct size, they will lack opacity which is necessary in order to produce a correct image of the subject photographed, and unless the small dots have the required opacity the plate when printed for etching purposes will permit too much light to pass through the smaller dots, thus causing flatness, lack of detail and a deviation from the original subject.

30 It is evident that a dot lacking sufficient opacity to make a print truly representative of the value the dot is supposed to represent, is defective. Therefore the object of my invention is to produce dots on a sensitized plate each having the required opacity and size to truly represent the tone value which it depicts.

35 The reason for the lack of opacity is that the whitest or highest lights or parts of the subject, record or photograph in a given period, to a greater degree of opacity than the lower lights or darker parts of the subject, consequently if the time of exposure is long enough to photograph the lesser lights or dark parts of the subject to secure the required opacity, then the high light dots will be exaggerated thereby giving an overexposed negative in the high lights in order to secure a correct exposure in the lesser lights.

40 It is evident that a large opening in the diaphragm will admit a greater volume of light and also permit a greater spreading of the light rays passing through the half tone screen, on account of greater angulation. It is also apparent that by reducing the volume of the reflected light rays which pass through the lens, by reducing the size of the aperture in the diaphragm, the angulation or spreading of the dots on the plate is modulated, whereby the high lights are retarded and the lower tones are intensified. From the foregoing it is evident that

volume of light alone cannot spread the dots to their proper tone relations, but must be mechanically controlled to balance volume and angulation; the volume decreasing as 5 the angulation increases and vice versa. The term "angulation" as used herein has reference to the angle of the light rays passing through the meshes of the half tone screen as controlled by the size of the dia- 10 phragm aperture and the extension of the camera bellows.

Since angulation for the spreading of the dots is necessary and a greater period of exposure is required to form an opaque small 15 dot from dark copy, as compared with a white copy; and also for the reason that the whitest or high lights are reflected through the entire lens, and the lower or darker rays are reflected through the central portion of 20 the lens, means which will modulate the volume by admitting a greater volume of light through the center of the lens than through its margin, relatively during a given period, will permit the small dark dots 25 to spread and photograph to the required opacity, without exaggerating the high light or large dots.

It has been found that a diaphragm mounted to revolve and having an aperture 30 shaped to admit light rays through its center during a major portion of the revolution and gradually diminishing in size toward the margin will give the results hereinbefore set forth.

35 A particular object of the invention is to carry out the photographing at a single exposure, which makes for a saving of time and expense and requires less skilled labor.

40 A frequent fault in half tone cuts is the blurring or ragged-edges dots and it has been found in tests of my method using the same mesh of screen, that the dots are more pronounced and clean cut and therefore a much higher grade of coarse mesh negatives, 45 such as are used in newspaper work, may be produced by my method by an unskilled operator.

Means for carrying out the invention will be hereinafter set forth and shown in the 50 accompanying drawings, wherein:

Fig. 1 is a longitudinal sectional view of a compound lens constructed for carrying out my improved method,

55 Fig. 2 is a diagram depicting the relative transmission of light rays through the stop used with the lens, and

Fig. 3 is a diagrammatical view of the stop disk and its supports.

60 In the drawings the numeral 10 designates a lens housing having a flange 11 at its rear end by which it may be fastened to the front of the camera. The housing has a vertical slot 12. In the housing are suitably mounted the component members A, B, C and D of compound lens, the members A

and B being in front of the slot and its members C and D in the rear thereof. The center of the slot is co-incident with the focal center of the lens.

In carrying out the invention a revolving stop disk 13 is employed. This disk is inserted in the slot 12 from the top and supported in tri-spaced grooved rollers 14, the center and lowest of which is driven by an electric motor 15. The disk (Figs. 2 and 75 3) has an eccentric stop opening 16, which I have found by experiments, gives most satisfactory results when having the heart shape shown, but I wish it expressly understood that the invention is not to be limited 80 to such a shape. The theory of the stop opening shown is, that when the disk is revolved at about one hundred revolutions per minute, the least restraint will be offered to the transmission of reflected light rays at 85 the center of the disk which is axially alined with the longitudinal axis of the lens, and that the transmission will be proportionally retarded or restrained outwardly from said center in the ratio of the intensity of the 90 light rays or tones.

A stop opening which extends on both sides of the center of the diaphragm and is bounded by a parabolic curve, has been found to give highly satisfactory results. 95

By referring to the diagram of Fig. 2 it will be seen that sixteen concentric circles are shown intersecting the opening or aperture 16, said circles being equally spaced from the center. The segment formed in 100 the smallest or central circle by the uncut portion 17 of the opening will obscure or interrupt less transmission of light than the segment in the next circle and so on out to the outer end of the opening, when said disk 105 is revolved. Viewed conversely the inner circle will permit the greatest transmission of light rays; while the outer circle will allow the least transmission of light rays. Therefore the disk in revolving will through 110 its stop opening 16 restrain or retard the transmission of light rays proportionally to their intensity, thus distributing the transmission radially of the stop opening and affording a greater opportunity for the passage of the low lights at the center than is 115 afforded the high lights at the outer end of said opening, the intermediate tones being restrained in proportion to their relative value. The amplitude of the light rays controls their intensity and by varying the amplitude through restraint of transmission, the intensity is governed.

In operating the camera the proper size of stop opening is determined in the usual 125 manner well known in this art; the motor is started and the disk 13 having the proper size of stop opening 16 is dropped into the slot 12 upon the rollers 14. The plate is placed and the exposure is made while the 130

disk is revolving. A single exposure is all that is required and such an exposure does not require nearly as much time as the three exposures which are usually made in photo-
5 engraving plants.

What I claim, is:

1. A device for controlling the transmission of light rays through a lens comprising a continuously rotated apertured diaphragm in constant operative relation for interrupting the passage of said rays according to their reflected intensity, whereby the rays of varying intensity are recorded in their proportional values. 10
2. A device for controlling the transmission of light rays through a lens comprising a continuously rotated apertured diaphragm for admitting a maximum passage of light rays through the center of the lens and diminishing radially of the lens the proportionate passage of light rays therethrough. 15
3. The method of controlling the passage of reflected light rays from a subject through a lens which consists in making a single exposure through a diaphragm continuously rotated during exposure and having an aperture for controlling the period of transition of the reflected rays of light from the respective parts of the subject according to the portion of the lens through which they pass. 20
4. An exposure diaphragm for a camera having an aperture extending on both sides of the center thereof and diminishing in area toward its outer end and means for continuously rotating said diaphragm during exposure. 25
5. The combination with a photographic lens of a diaphragm continuously rotated during exposure and having an eccentric aperture having its greatest area at the center of the diaphragm. 30
6. A device for controlling the transmission of light rays through a lens comprising a diaphragm having an aperture at the 45 focal center of the lens having its walls extending upon a parabolic curve to each side of said focal center and means for continuously rotating said diaphragm during exposure. 50
7. A device for controlling the transmission of light rays through a lens comprising a diaphragm having an aperture adjacent the focal center of the lens having its walls extending upon a parabolic curve to 55 each side of said focal center, and means for revolving said diaphragm continuously during exposure.
8. A device for controlling the transmission of light rays through a lens comprising a disk continuously rotated during exposure and having an aperture with walls extending radially and eccentrically to the focal center of said lens. 60
9. A device for controlling the transmission of light rays through a lens comprising a disk continuously rotated during exposure and having a substantially heart-shaped aperture disposed with its base at the 65 focal center of the lens. 70
10. A device for controlling the transmission of light rays through a lens comprising a disk continuously rotated during exposure and having a substantially heart-shaped aperture disposed with its base at the 75 focal center of the lens, a casing comprising opposite lens carrying members spaced apart, a driving member between said members upon which the disk is supported, and means for rotating said member. 80

In testimony whereof I affix my signature.

JEWETT G. P. EVANS.
